UNITED STATES PATENT OFFICE.

WILLIAM SEBELIN, OF CAMAS, MONTANA.

REENFORCING SPLINT FOR WAX FOUNDATIONS.

Application filed March 31, 1924. Serial No. 703,255.

To all whom it may concern:

Be it known that I, WILLIAM SEBELIN, a citizen of the United States, residing at Camas, in the county of Sanders and State 5 of Montana, have invented new and useful Improvements in Reenforcing Splints for Wax Foundations, of which the following is a specification.

This invention relates to novel means for 10 supporting the wax foundation in the brood frames of bee hives.

The need for such a provision arises from the fact that the foundation is quite plastic at the hive temperature and apt to sag when 15 unsupported, particularly near the top, when weighted down with a mass of bees engaged in drawing the comb. The result of this sagging or stretching is to enlarge or deform the cells of the hexagonal pattern 20 stamped upon the foundation, rendering them unfit for worker brood, so that disproportionate areas of the comb become unproductive, being left vacant by the queen or given over to the rearing of drone 25 brood.

Many expedients have been tried to prevent stretching of the foundation, the most widely practiced being the reenforcing of the foundation by horizontal wires laced 30 from one side of the frame to the other and embedded in the foundation. This is not an ideal expedient, however, because the wiring and embedding is a tedious undertaking and the foundation is inevitably weakened on 35 the lines where the wires are embedded and the wires have a tendency to cut through the ribs which form the peripheral walls of the hexagonal cells, thus reducing the effective thickness of the foundation merely 40 to that of the bottom wall of the cells. Moreover, after a frame has been properly wired the act of positioning it in the hive sometimes requires considerable forcing 45 upon the top bar which is apt to twist the frame somewhat from its true rectangular shape and to loosen the wiring and cause bulging of the foundation. Already-wired foundation has also been tried but this requires especially constructed frames with 50 means for clamping the ends of the wires at both sides or both ends of the frames according to whether the wires run horizontally or vertically. In all cases where several strands of wires are used the cells intersected by the wires are likely to be

rejected by the bees, reducing to an appreciable extent the brood rearing area of the frame.

Vertical splints also have been tried, but so far these have been for the most part impractical make-shifts and their use has 60 been abandoned as not producing satisfactory results.

The object of the present invention is to provide means cooperating with the top and bottom bars of the brood frame for 65 supporting the foundation, said means clampingly engaging the foundation at opposite sides and in the same plane without cutting through the ribs which form the walls between adjacent cells and therefore 70 maintaining the full strength of the foundation.

Another object of the invention is to provide said means of considerable width, yet not exceeding the width of the top bar of 75 the frame, so that, when the comb is built in adherence to said means, it will be firmly supported in a direction at right angles to the plane of the foundation. Still another object of the invention is the provision of 80 foundation supporting means which can be applied to a frame without any disfigurement or alteration of the latter, it not being necessary to even subject the frame to the driving of nail-holes therein.

A further object of the invention is to provide foundation supporting means comprising a pair of splints co-acting to engage the foundation between them in clamping relation, said splints being secured by a 85 bendable member adapted to encompass the top bar of the frame, the lower ends of said splints being rabbeted for engagement with the sides of the bottom bar and the ends of said splints being held together by means 90 bridging said bottom bar.

With the above and other objects in view, my invention consists in the improved reenforcing splints for wax foundation illustrated in the accompanying drawings, described in the following specification, and particularly claimed, and in such variations and modifications thereof as will be obvious to those skilled in the art to which my invention relates.

In the drawings accompanying and forming a part of this specification, and where in the preferred embodiment of my invention is illustrated:

Figure 1 is a side elevation of a frame showing my invention applied thereto.

Figure 2 is a top view of the frame on an enlarged scale, parts thereof being broken away.

Figure 3 is a cross section taken along the line 3—3 of Figure 1.

Figure 4 is a cross sectional view of two frames in the relative position which they 10 occupy within the bee hive, showing the preservation of the bee spaces between adjacent frames provided with my invention.

Figure 5 is a cross sectional view of an 15 upper portion of the frame, indicating the manner in which my invention is applied.

Referring now in detail to the several 20 figures, the numeral 1 represents a frame having the top bar 2 and bottom bar 3, the latter being slightly narrower than the 25 top bar. The end pieces 4 and 5 are connected in any suitable manner to the top and bottom bars, for instance by dovetailed joints as shown, the top bar projecting beyond the end pieces at 6 and 7, 30 to engage cleats or rabbets, (not shown) on the inner sides of the ends of the bee hive, by means of which the frame is suspended. Usually eight or ten frames are arranged side by side in parallel relation

35 within the hive.

In the practical embodiment of the frame used for illustrative purposes, the lower face of the top bar is cut away longitudinally forming a rabbet 8 reaching substantially to the longitudinal center of the lower surface of the top bar and forming a shoulder 9 against which the upper edge of the sheet of foundation 10 rests, said foundation being held in place by a relatively thin batten 11 seated in the rabbet 40 and which is pressed into close frictional engagement with the foundation at the upper edge of the latter and nailed securely in place in this position. The foundation 45 generally terminates a slight distance above the bottom bar of the frame as is indicated at 12 in Figure 4. So much of the structure as has been described up to this point is old in the art.

50 When a frame furnished with foundation in the manner indicated is placed in the bee hive the bees proceed to draw it out into comb. To do this they gather upon the foundation in great numbers. The 55 temperature of the hive is sufficiently elevated to maintain the wax foundation in a rather pliable state so that the weight of the bees is apt to stretch it, causing it to sag downwardly and deforming or enlarging the hexagonal cells which are stamped upon the foundation. These cells are normally of exactly the size acceptable to the queen bee for the rearing of worker brood, but when they are deformed or enlarged they are ignored by the queen or

used merely for the rearing of drone brood. As the productiveness of the hive depends upon the number of worker bees, and the number of the latter is dependent upon the area of the comb available for the rearing of the worker brood, it is evident that the productiveness of the hive is seriously reduced by the stretching of the foundation. To prevent said stretching I have devised means, the same constituting my invention, 75 which is here shown as applied to a frame of the ordinary Hoffman construction but which may be so varied in form and configuration as to be adaptable to almost any 80 of the known forms of frame, without departing from the principle of the invention.

My invention consists of a pair of narrow rigid splints 13 and 14 united by a bendable member 15, the latter being of 85 sufficient length to pass around the top and sides of the top bar, and being formed with suitable means at its ends for permanent engagement with said splints. Said engaging means is shown as consisting of a pair 90 of oppositely disposed leaves 16, preferably made integral with the bendable member 15, and embracing the opposite sides of the splint. Any suitable means may be used 95 for securing said leaves to said splints in a permanent manner such as the punched indentation 17 shown in Figures 4 and 5. The bendable member 15 is preferably constructed of flat sheet metal so as to lie close to the top bar when bent thereabout and thus oppose no obstruction to the free 100 passage of bees longitudinally of the frame either above or at the sides of said top bar.

The splints 13 and 14 are recessed at their 105 lower ends as shown at 18 so as to embrace both the top and sides of the bottom bar, said splints being held in place by means such as the wide staple 19, the latter bridging the bottom bar and penetrating the ends 110 of the splints which overhang the bottom bar. By means of this construction no alteration or disfigurement of the frame is necessitated, not even the driving of a single 115 nail into the frame structure. When it is desired to remove the splints a prying member, such as the hive tool or a screw-driver is placed between the staple 19 and the bottom bar. When the staple has been removed the splints can be spread in the manner 120 shown in Figure 5 and lifted from the top bar leaving the frame intact. The thickness of the splints is preferably such as to make them terminate flush with the sides of the top bar. This provides a beeway between 125 the splints of adjacent frames as shown at 20 in Figure 4. At the same time, the width of the splints provides a support for the adherence of the comb throughout its entire 130 thickness in a direction at a right angle to

the plane of the foundation thus affording a support which cannot be furnished by a wire or other reenforcing means which lies entirely within the foundation. Moreover, 5 when the splints are positioned in clamped relation against the foundation they merely press it frictionally without severing or otherwise destroying the ribs or walls between the adjacent cells, thereby avoiding 10 the weakening of the foundation which, as stated hereinbefore is a defect of all wiring arrangements.

While I have here shown my invention as constituted in part by a flat sheet metal 15 bendable member, it is well within the spirit of the invention to substitute other bendable means such as a round wire for holding the splints together. When sold as an article of manufacture the splints may occupy the 20 position shown in Figure 4 with the bendable member already bent to conform with the shape of the cross section of the frame or if desired said bendable member may be shipped unbent and afterwards made to 25 conform to the cross section of the top bar when applied to the frame.

It is to be understood that the use of my 30 reenforcing splints is not confined to frames for the brood chamber but that they are equally well adapted to reenforce the comb in those frames which are to be used for the production of extracted honey. It is a matter of common knowledge that such 35 combs are subjected to strain in the centrifugal extractor which sometimes stresses them to the breaking point. The use of the rigid vertical splints of my invention affords adequate support for the combs during the extracting process.

40 While I have above described what I have found to be a very practical embodiment of my invention, it is nevertheless to be understood that the reenforcing splints for wax foundation may also be exemplified in 45 numerous other alternative constructions and I accordingly reserve the right of adopting all such legitimate changes as may be fairly embodied within the spirit and scope of the invention as claimed.

50 Having described my invention what I claim as new and desire to secure by Letters Patent, is:—

1. A foundation support for use in a 55 frame for holding honey-comb comprising a pair of splints adapted to engage the opposite sides of a sheet of foundation in said frame and means embracing the top and sides of the top bar of said frame and connected at its opposite ends to said splints.

60 2. A foundation support for use in a frame for holding honey-comb comprising a pair of splints adapted to engage the opposite sides of a sheet of foundation in said frame and bendable means embracing 65 the top and sides of the top bar of said frame

and connected at its opposite ends to said splints.

3. A foundation support for use in a frame for holding honey-comb comprising a pair of splints adapted to engage the 70 opposite sides of a sheet of foundation in said frame and flat bendable means embracing the top and sides of the top bar of said frame and connected at its opposite ends to said splints.

4. A foundation support for use in a frame for holding honey-comb, comprising a pair of splints adapted to be positioned between the top and bottom bars of said frame to engage the opposite sides of a sheet of foundation held therein, means for embracing the top and sides of said top bar and connected at its opposite ends to the upper ends of said splints, and means for 80 bridging said bottom bar and engaging the lower ends of said splints to hold them together.

5. A foundation support for use in a frame for holding honey-comb, comprising a pair of splints adapted to be positioned between the top and bottom bars of said frame to engage the opposite sides of a sheet of foundation held therein, bendable means for embracing the top and sides of said top bar and connected at its opposite ends to the upper ends of said splints, and means for bridging said bottom bar and engaging the lower ends of said splints to hold them together.

6. A foundation support for use in a frame for holding honey-comb, comprising a pair of splints adapted to be positioned between the top and bottom bars of the frame and to engage the opposite sides of a sheet of foundation held therein, the lower ends of said splints being rabbeted to overhang the sides of said bottom bar, means for embracing the top and sides of the top bar and connected at its opposite ends to the upper ends of said splints, and a staple for bridging the bottom bar and adapted to be driven into the overhanging portions of said splints to hold them together.

7. A foundation support for use in a frame for holding honey-comb, comprising a pair of splints adapted to be positioned between the top and bottom bars of the frame and to engage the opposite sides of a sheet of foundation held therein, the lower ends of said splints being rabbeted to overhang the sides of said bottom bar, bendable means for embracing the top and sides of said top bar and connected at its opposite ends to the upper ends of said splints, and a staple for bridging the bottom bar and adapted to be driven into the overhanging portions of said splints to hold them together.

8. A foundation support for use in a

frame for holding honey-comb, comprising a pair of splints adapted to be positioned between the top and bottom bars of the frame and to engage the opposite sides of a sheet of foundation held therein, the lower ends of said splints being rabbeted to overhang the sides of said bottom bar, flat bendable means for embracing the top and sides of the top bar and connected at its opposite

ends to the upper ends of said splints, and 10 a staple for bridging the bottom bar and adapted to be driven into the overhanging portions of said splints to hold them together.

In testimony whereof I have hereunto set 15 my hand.

WILLIAM SEBELIN.
